UNITED STATES PATENT OFFICE.

GEORGE A. LONG, OF SEATTLE, WASHINGTON.

AUTOMATIC FEEDING DEVICE FOR TRACK OR FLANGE OILERS.

Application filed September 8, 1924. Serial No. 736,491.

My invention relates to improvements in automatic feeds for track or flange oilers arranged for installation on all vehicles that run on tracks, and the principal objects of the invention are to provide a feed adapted for operation by the pivotal movement between the main body portion and the truck member of such vehicles whereby the lubricant is automatically supplied in accordance with the tangential variation and directly in proportion to the curvature of the track. Further objects are to provide an automatic feed of simple and durable construction, that is reliable and efficient in operation, close fitting and direct in its action, and which may be thrown out of operation at any desired moment.

With the above and other objects in view which will appear as the description proceeds, the invention consists of the novel construction, adaptation, arrangement and combination of parts hereinafter described and claimed. These objects are accomplished by devices illustrated in the accompanying drawings, wherein:—

Figure 1 is a diagrammatic view in side elevation of certain parts of a locomotive engine showing my automatic feed device installed thereon;

Fig. 2 is a similar view in front elevation;

Fig. 3 is a detail view in central vertical section of the lubricant supply tank;

Fig. 4 is a detail view in central vertical section of the feed control valve; and

Fig. 5 is a fragmentary detail view in central vertical section of the discharge end of the nozzle.

Referring to the drawings throughout which like reference numerals designate like parts, the numeral 5 indicates the main engine frame as a whole, and the numeral 6 designates an engine truck frame. Said main frame carries the upper saddle 7 of the engine which is revolvably mounted on the lower saddle 8. Said lower saddle is suspended from the truck frame 6 by hangers 9, and a center pin 10 holds the two saddles together and allows them to revolve with respect to each other in the usual manner. The numeral 11 designates, preferably, one of the lead wheels of the engine which helps to carry the truck frame 6 through the medium of a journal box 12.

In detail my invention comprises a lubricant supply tank 13 which may be mounted

on the main engine frame 5 by any suitable means. A tube 14 is arranged to supply pressure from a steam or air compressor tank (not shown) to said lubricant tank as 60 will be readily understood. Said lubricant tank is provided with a filling spout 15, and a piston 16 mounted therein is adapted to be raised by means of a rod 17 which passes upwardly through a stuffing box 18. While 65 this piston arrangement is shown in the drawings, it is not considered necessary, as the air or steam pressure would force the lubricant downwardly if same were eliminated.

A depending pipe 19 communicates with the bottom of the lubricant tank 13 and is provided with a control valve 20. The core 21 of said valve is provided with a conduit 22, and, by means of an exterior handle 23, 70 said core is turned in the direction indicated by the arrow in Fig. 4 to establish a passageway for the lubricant through said conduit as more fully hereinafter set forth. The outer end of said handle is provided with a knob 24 for the reception of the hooked end of a lever 25 that is pivotally connected with the truck frame 6, as at 26. It will be understood that I do not limit myself to this specific arrangement and that same is shown as one means for reducing 75 my principle to practice.

An elbow 27 joins the depending pipe 19 with a horizontally disposed pipe 28 that is provided with a ball and socket connection 90 29, and a second elbow 30 joins said horizontal pipe to a vertically disposed pipe 31 which is provided with a ball and socket connection 32. Said vertical pipe joins a ball and socket connection 33 whose socket portion is provided with a block member 34 secured by studs 35 against the outer face of a bracket 36 bolted to the box 12. Said studs pass through a vertical slot provided in said bracket, as clearly indicated in Fig. 2 of the drawings, to permit vertical adjustment. The ball portion of said connection is provided with a depending pipe 37 and a nozzle 38 is threadedly secured thereto. The discharge end of said nozzle is provided with a threaded recess 39 adapted to receive a plug 40 having an outlet orifice 41 therein, and it will be understood that plugs having different sizes of orifices may be substituted therefor in accordance with the consistency 100 105 of the lubricant to be used.

It may be stated that the ball and socket

connection 33 together with the associated pipe 37 and nozzle 38 constitute the principal elements of a track lubricator similar in all respects to the track lubricator described in my prior Patent, Number 1,497,177, dated June 10, 1924. All of the details of same are fully covered in said patent and no specific recital thereof is herein considered necessary. I consider that a track lubricator embodies the most practical and efficient means for supplying the lubricant and I have therefore shown my present invention in conjunction with such means, although it will be expressly understood that same may be used in combination with any form of flange oiler or other similar device and is equally applicable thereto.

In practical usage it is desirable to install a feed device on both sides of the locomotive adjacent the inner side of the foremost or lead wheels and at a sufficient distance forward therefrom to insure against contact therewith when the nozzle meets with an obstruction. It is likewise essential that same be secured to some part of the engine which retains a fixed relation with the track, such as the journal box 12, so the nozzle 38 will always be in engageable relation with the gauge side of the rail head. As hereinbefore mentioned, the studs 35 pass through a vertical slot in the bracket 36 thus providing means for vertical adjustment to compensate for any radial variation of the wheels.

When the vehicle is running on straight track the valve 20 is normally closed, as shown in Fig. 4, and no lubricant can pass therethrough. The conduit 22 is so positioned that upon encountering the slightest curve same will instantly open and lubricant will be supplied forthwith. It is well known that the centrifugal force of a train going around a curve increases the weight on the outer rail and decreases that on the inner rail, resulting in a grinding abrasion of the inner side of said outer rail where same impinges the wheel flanges, and thus causes an embrittled condition along the gauge side of the rail head and the consequent wearing down of the wheel flanges.

It will be understood that the control

valve 20 on the device which is positioned on the outer rail curve side will open while the one on the inner side will close simultaneously, and the greater the curve the more lubricant will be supplied. The ball joints 29 and 32 will furnish flexibility and allow for any inequality of movement in the pipe connections. The lever 25 may be lifted if, at any time, it is desired to throw the apparatus out of operation.

It will now be obvious that I have provided a device which will automatically supply the lubricant at all points where needed and directly in proportion to the needs, thus obviating much of the flange friction that has heretofore resulted in an enormous loss in track and wheel deterioration, track resistance and waste of energy, derailment and damage to life and property.

From the foregoing description taken in connection with the accompanying drawings, the construction and operation of my device will be readily apparent, and, while I have described the invention with considerable particularity, it will be understood that I intend no limitations within its scope and spirit except in so far as are imposed by the appended claim.

Having thus described my invention what I claim and desire to secure by Letters Patent of the United States is:—

A railway vehicular automatic feeding device for track or flange oilers comprising a lubricant supply tank, gravity pressure means for the lubricant within said tank, a discharge member for applying the lubricant to the track rails, adjustable supports for said discharge member, pipe connections between said tank and discharge member having flexible joints, a globe-valve for said pipes having a conduit therethrough with a funneled receiving end that is normally closed when the vehicle is running on straight track, and lever means pivotally secured to the truck portion of the vehicle adapted to revolvably open the valve conduit and discharge lubricant upon the track rails when the wheels of said truck encounter a curve in said track substantially as specified.

GEORGE A. LONG.
